UNITED STATES PATENT OFFICE

CLARENCE D. TRUSSELL, OF POUGHKEEPSIE, NEW YORK, ASSIGNOR TO TRUSSELL MANUFACTURING COMPANY, OF POUGHKEEPSIE, NEW YORK, A CORPORATION OF NEW YORK

HINGED BOOK COVER

Application filed July 31, 1928. Serial No. 296,487.

This invention relates to book covers of that type wherein the back and sides are united by hinge eyes and pintles at their junction. In previous applications I have set forth various constructions whereby the sides and backs of leather or leather-like material are provided with metal hinge plates embedded within the thickness of the material, with hinge eyes appearing at the edges of the back or sides where they are to be united by the usual pinte.

In my application Serial No. 120,053, filed July 2, 1926, is set forth a construction wherein the curved back of the book has embedded within it a metal plate having hinge eyes emerging beyond the edges of the back, and the sides have hinge plates inserted from the inner side into pockets, with their eyes also emerging beyond the edges in alternation with those of the hinge plate in the back; the sides are first grooved, and from the groove the leather is split in either direction to form the pocket; after the hinge plate is inserted, the groove may be closed to make a neat finish by filling it with a strip of leather which is cemented in place.

My application Serial No. 225,762, filed October 12, 1927, illustrates a similar method of applying the hinge plates in the cover sides; in this case, however, the hinge eyes do not protrude beyond the edges of the back and sides, but are themselves embedded in or covered by the leather or like material.

The present invention is adaptable to either of the constructions set forth in my said applications. It is characterized by the formation of the metal hinge plate with a rib which enters the groove formed in the cover side so as to close that groove, thus forming a neat finish without the necessity of gluing in a strip of leather, while also contributing to the stability of the structure.

My present invention also provides means for drawing down and securely fastening the flaps of leather forming the margins of the

pocket which receives the hinge plate, whereby to avoid the necessity of cementing down these flaps. To this end the hinge plate is formed with spurs or points struck up from it at a suitable angle, so that when it is put in place and subjected to pressure, the spurs penetrate the leather and draw the latter down flat, embedding themselves in the leather and making a smooth and imperceptible finish.

Figure 1 of the accompanying drawings is a fragmentary perspective view showing a portion of a book cover constructed according to this invention, one of the sides being detached, and the view being in section to more clearly show the construction.

Fig. 2 is a perspective view of a portion of one of the hinge plates.

Fig. 3 is a fragmentary perspective view showing one way in which the plate may be put in place.

Fig. 4 is a perspective view illustrating the preparation of the leather cover material.

Referring to the drawings, A shows the rounded back of a book, and B, B, the sides, these three elements being united by mechanical hinges at their junction, the hinges being of the usual form with interlocking eyes connected by a hinge wire or pinte C, all as is well understood. The back and sides may be of leather or any similar or suitable material. In the description I will assume that leather is used, it being understood that any equivalent material or any leather substitute may be used instead.

The hinges are formed by means of hinge plates of sheet-metal embedded in the back and sides. In the particular construction shown, the back is formed with two hinge plates D, D, which meet edge to edge at the middle and at their outer sides are formed with the hinge eyes E, E. The plates D, D, might be a single plate, as in my said application No. 120,053; but for certain constructions of loose leaf books it is preferable to

make them separate (as in my application No. 225,762, where they are united by turned-down ears or tongues *a, a*, to an inner spring-plate *F* which is itself a well-known element 5 of loose-leaf binding mechanisms). In the particular construction shown, the back is on its inner side divided at *b*, and is slotted therefrom in both directions to form a pocket, and the plates *D, D*, are inserted at the division or groove *b*, the depth of the pockets being sufficient to receive the eyes on the plates. In the construction shown the eyes are embedded in the marginal portion *c* of leather, so as to conceal the hinge eyes, this being 10 the construction shown in my said application No. 225,762; if it is not desired to conceal the hinge eyes, they may project beyond the leather, as shown in my said application No. 120,053.

20 The present invention relates more particularly to the hinge plates *G, G*, for the sides of the book. The leather of each side is first grooved in the manner set forth in my said previous applications. From the bottom of 25 the groove the leather is then split in both directions, the leather thus prepared being as shown in Fig. 4, where the groove is lettered *d*, and the pockets formed by the slitting or splitting are lettered *e* and *f*. These 30 pockets may go to the extreme ends of the book, or may stop short thereof, as desired.

The plate *G* which is shown separately in Fig. 2 is formed with an abrupt corrugation or rib *g*, the position of which coincides with 35 that of the groove *d*, so that when the parts are assembled, this rib will fill the groove. When thus located, as shown in Fig. 1, the rib should exactly fill the groove, its inner face lying flush with the inner face of the 40 cover side, so as to make a neat finish.

It is desirable after inserting the hinge plate in the cover side, to fasten down the leather flaps formed in cutting the pockets. To do this by means of glue or cement is a 45 somewhat difficult and troublesome operation which must be performed by hand. It is desirable to substitute for it an easy and effective means for fastening down these leather flaps, which can be more rapidly and 50 cheaply performed by a machine operation. For this purpose I provide the plate *G* with one or more rows of spurs *h, h*, as shown in Fig. 2, these spurs being adapted to enter the leather of the flaps near the margins thereof, 55 and under pressure which may be applied when the flaps have been smoothed down in place, to penetrate the flaps and hold them down against the plate. The size and shape of the spurs is important in order to secure 60 the best results. The spurs should be nearly enough perpendicular so that they will assuredly enter the leather, and yet should incline enough so that as they enter the leather they will tend to partially fold down toward 65 the plate and will thereby force their way

into the leather and hold it securely down. Another function of the inclined spurs is to draw the leather tight, so as to prevent any looseness or any ridging of the leather on the inner side of the cover. Thus the spurs on 70 entering the leather tip over slightly in direction toward the rib *g*, and consequently draw the leather away from the bottom of the pockets on either side, so as to strain the leather against the hinge eyes on the one side, or the edge of the metal plate on the other side. This result is best attained by making the plate an exact fit for the pocket, which can be readily accomplished when the pockets 75 are cut by machinery to fit the plates. 80

The plate *G* may be made flat, as shown in Fig. 2, or it may be struck up initially in angular form, as shown in Fig. 3. The latter shape facilitates insertion in the pockets, and is especially desirable when the pockets 85 are closed at their ends. The plate being inserted, the leather flaps are drawn closely parallel with the plate, and the cover side is then placed in a press and subjected to pressure which flattens the side, and in so doing 90 causes the spurs to enter the marginal portions of the pocket flaps and draw them tight. For either operation the same result is produced, the final construction being as 95 shown in Fig. 1.

I am aware that metal spurs have been used to fasten a metal plate to leather, but believe it to be new to apply these spurs for fastening the flaps or marginal portions of a pocket, and also that it is new to apply inclined spurs so that in entering the leather they will bend down under pressure and draw the leather tight. 100

My invention is not necessarily limited to the precise construction shown and described, 105 but is subject to a reasonable latitude of variation within the scope of the appended claims.

I claim as my invention:

1. In a hinged book cover, the cover material formed with a groove on one side and with a pocket communicating with the groove, and a metal plate inserted in said pocket and having a rib entering said groove. 110

2. In a hinged book cover, the cover material formed with a groove on one side and with pockets extending to opposite sides of, and communicating with, the groove, and a metal plate inserted within said pockets and having a rib entering said groove. 115

3. In a hinged book cover, the cover material formed with a groove on one side and with pockets on opposite sides of said groove, and a metal plate inserted in said pockets having a rib filling said groove, and formed with spurs adjacent said rib adapted to enter the marginal portion of the cover material and hold it securely adjacent said rib. 125

4. In a book cover comprising an integral material split to form a pocket within its 130

thickness, the opening to said pocket formed as an incision in the material and the pocket extending to both sides of such incision, and a metal plate inserted in said pocket, said plate formed with two parallel series of spurs extending on opposite sides of such incision, adapted under pressure to enter said material and to become bent down therein, and the respective series adapted to fasten down against the plate the respective flaps on opposite sides of said incision.

In witness whereof, I have hereunto signed my name.

CLARENCE D. TRUSSELL.
